United States Patent Office

Des. 204,433
Patented Apr. 12, 1966

204,433

HELICOPTER

Edward S. Cruz, Van Nuys, Calif., assignor to Lockheed
Aircraft Corporation, Burbank, Calif.

Filed July 15, 1965, Ser. No. 86,165

Term of patent 14 years

(Cl. D71—1)

FIG. 1

FIG. 2

FIG. 3

FIG. 4

FIGURE 1 is a perspective view of the lower side of the helicopter embodying my new design;

FIG. 2 is a side elevational view thereof;

FIG. 3 is a front elevational view thereof; and

FIG. 4 is a top plan view thereof.

I claim:

The ornamental design for a helicopter, substantially as shown and described.
